DEVICE FOR OPENING CANS

Harry L. Dazey, Clayton, Mo., assignor to Dazey
Churn & Manufacturing Co., St. Louis, Mo., a
corporation of Missouri

Application March 27, 1935, Serial No. 13,213

9 Claims. (Cl. 220—52)

This invention relates to a device for opening cans that employ a rip-strip whereby they may be opened. The invention includes a clamping mechanism for gripping the strip and means for simultaneously winding the strip from the can and revolving the latter.

It is an object of this device to provide a strip remover that will engage the strip and exert an evenly distributed tension, longitudinally of the strip.

It is a further object to provide a strip remover that will be capable of engaging a very small portion of the strip, such as may exist in case the strip is broken, and remove the same.

Other objects and advantages will be set out in the description hereinbelow taken in connection with the accompanying drawing in which:

Fig. 1 is a plan of the device.

Fig. 2 is an elevation of the same.

Fig. 3 is a section on the line 3—3 of Fig. 2.

In the drawing, 10 indicates a can closed by a rip-strip 11 that is normally provided with a projecting tab portion at the end thereof to be engaged by a key or the like for the removal of strip 11. The present invention is designed to obviate the use of such keys. It includes two channel-shaped handle members 13 and 14 pivoted together at 15. Cooperating rollers 16 and 17 are mounted near pivot 15 in the channels of respective members 13 and 14. These rollers may be knurled or otherwise provided with gripping surfaces, as desired. To one of these rollers, here shown as upper 16, is fastened a crank 18 by which roller 16 may be rotated. The handle members are provided with depending walls 19, as shown in Fig. 2, these walls being set back from the pivot supporting portion 15. By this means, a shoulder is provided that may engage the top edge of a can. As will be seen, the rollers 16 and 17 engage against the bead on the can. If desired, an abutment 20 may be provided on each channel, below its roller, to accommodate for the thickness of the beading on the can whereby to maintain these rollers vertical.

The operation of the device is as follows:

The free end of the rip-strip is bent out to project from the side of the can. The handles 13 and 14 are parted, thereby parting rollers 16 and 17. The shoulder formed by the pivot supporting portion is engaged over the top edge of the can adjacent the rip-strip, with the free end or tab of the rip-strip between the rollers 16 and 17. With one hand on the handles 13 and 14 are squeezed together thereby tightly gripping the rip-strip between the rollers 16 and 17. With the

other hand the crank 18 is then rotated, causing rotation of roller 16, drawing the rip-strip 11 off the can, and at the same time revolving roller 17, and also the can.

Providing abutment 20 insures that the rollers 5 will be substantially parallel to the axis of the can. Hence the tension on the winding strip will be distributed evenly across it, and will be in the direction of the length of the strip. This means that the strip will be drawn off smoothly without 10 any tearing action, and with the likelihood of breaking minimized.

Should the strip become broken, only a small projecting portion is necessary for reinstating the operation, since such is large enough to be grasped 15 between the rollers. Even though the projecting portion is narrow, the even distribution, and longitudinal direction of the tension produced by this can opener, will reduce to a minimum the chance of breaking it.

The invention having been described, what is claimed is:

1. A can opening device of the kind described, including a pair of handles, a pair of rollers, one roller on each handle, said handles being pivoted 25 together, whereby said rollers may be brought together or moved apart, and means to rotate at least one of said rollers.

2. A device of the kind described, including a pair of pivoted handles, a roller on each handle, 30 and said rollers being adapted to be brought together or moved apart, means to support said rollers adjacent the side of a container, and means to rotate at least one of said rollers.

3. A device of the kind described, including a pair of pivoted elements, a roller on each element, said rollers being adapted to be brought together upon movement of said pivoted elements, means overhanging the top of a container, 40 and a crank connected with one of said rollers whereby said roller may be rotated.

4. A device for opening a container having a rip-strip for opening the same, including support means for engaging a container, a pair of 45 rollers on the support to engage the rip-strip, means to force the rollers together to engage the rip strip between them, and means to rotate at least one of the rollers whereby to remove the rip-strip.

5. A device for opening containers having rip-strip for opening the same, including support means for engaging a container, a pair of rollers on the support to engage the rip-strip of the container, means on the support to space 55

one end of the rollers from the can, and means to rotate at least one of the rollers to remove the rip-strip.

6. A device of the kind described, having a pair of pivoted, channel-shaped handle members, a roller mounted in each handle member, said roller being spaced from the pivot of the handles, and said channel portions being cut away to said rollers, whereby to provide a shoulder portion, and means to rotate one of said rollers.

7. A device of the kind described, including two elements, each having a top wall portion and a side wall portion, pivot means uniting said top wall portions of said elements, rollers, one roller being mounted in each element and spaced from said pivot, and both of said side wall portions being cut away back at least to said rollers, whereby to form a shoulder defined by said top

wall remaining, and said rollers, and means for rotating at least one of said rollers.

8. A device for removing rip strips from cans, including a pair of members each having an extension at one end thereof, means movably joining said members at said extensions, a roller on each member spaced inwardly from said extension, said rollers being adapted to be brought together by movement of said members and to engage the rip strip therebetween, and means to 10 rotate one of said rollers.

9. A device for removing rip strips from cans including a pair of opposed rollers, a member supporting each roller, said members being adapted to be brought together to engage the 15 rip strip between the rollers, and means to rotate one of said rollers to remove the rip strip.
